UNITED STATES PATENT OFFICE.

CHARLES E. BEARDSLEY, OF WATERBURY, CONNECTICUT, ASSIGNOR, BY MESNE ASSIGNMENTS, TO THE BEARDSLEY AND WOLCOTT MANUFACTURING COMPANY, OF WATERBURY, CONNECTICUT, A CORPORATION OF CONNECTICUT.

TOILET-ROLL HOLDER.

Application filed August 28, 1925. Serial No. 53,087.

This invention relates to bathroom wall fixtures, and more particularly to a holder for a roll of toilet paper adapted to be attached to the wall of said bathroom.

5 One object of this invention is to provide a holder of the above nature adapted to be made from porcelain or other similar material and constructed in the form of a housing, having its sides and top partially enclosing, 10 closing the paper roll carried therein.

A further object is to provide a device of the above nature which will be simple in construction, inexpensive to manufacture, easy to install and manipulate, compact, 15 ornamental in appearance, and very efficient and durable in use.

With these and other objects in view, there has been illustrated on the accompanying drawings one form in which the invention 20 may conveniently be embodied in practice.

Fig. 1 represents a side view, partly in section, of the toilet roll holder as it appears in operating position upon a wall with a roll of paper contained therein.

25 Fig. 2 is a front view of the same.

Referring now to the drawings in which like reference numerals denote corresponding parts throughout the several views, the toilet roll holder, herein disclosed, comprises 30 a housing having a flat rear vertical wall 10 adapted to be secured by screws 11 to a wall 12 of a bathroom. Extending forwardly from the rear wall 10 are a pair of flat tapered side walls 13 and 14, each of which 35 is formed substantially in the shape of a sector of a circle. The sections 13 and 14 are apertured near their front ends 15 and 16 to receive a locking bolt 17, preferably of metal, adapted to be held in said apertures by 40 means of a pair of ornamental nuts 18 and 19.

A hollow mandrel member 20, preferably constructed of wood and having beveled ends 21, is journaled on the bolt 17 and is adapted 45 to carry a paper roll of the usual standard size. The length of the mandrel 20 is slightly greater than the distance between the side walls 13 and 14, and in order to permit the mandrel to be readily inserted in 50 position, said side walls are provided in the bottom inner edges of their front ends 15 and 16 with a pair of vertical slots 22 and 23 adapted to form guideways for the extremities of the mandrel 20.

In operation, when it is desired to insert 55 a toilet paper roll 24 in the roll holder, said roll 24 will be slipped over the mandrel 20, after which the mandrel will be moved up in the slots 22 and 23 as far as it will go. The center hole of the mandrel will then be 60 in alignment with the apertures in the side walls 13 and 14. The locking bolt 17 will then be passed laterally through the apertures of the side sections 13 and 14, and through the interior of the hollow mandrel 65 20. The ornamental nuts 18 and 19 will next be screwed upon the threaded ends of the bolt 17, after which the device will be ready for use.

One advantage of this invention is the extremely rigid construction which is attained by providing the roll holder with thick reinforced walls, thus permitting the manufacture of the device out of porcelain or other frangible material, with the minimum 70 danger of breakage.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all 75 80 the modifications and embodiments coming within the scope of the following claims.

Having thus fully described the invention, what is claimed as new, and for which it is desired to secure Letters Patent, is:

1. In a toilet roll holder, a housing having a rear section for attachment to the wall of a room, a pair of forwardly extending side sections having a pair of vertical slots extending up from the bottom edges thereof, a hollow roll-holding mandrel adapted to be slid up through said slots and held in operating position thereby, and a rod passing through said side sections and said mandrel for locking said mandrel in said slots. 95

2. In a toilet roll holder, a housing having a rear section for attachment to the wall of a room, a pair of forwardly extending side sections, having a pair of vertical slots extending up from the bottom edges thereof, a roll-holding mandrel adapted to be slid up through said slots and to be positioned thereby, and a rod passing through said side 100 105 110

sections and said mandrel for locking said mandrel in said slots.

3. In a toilet roll holder, a housing adapted to be attached to the wall of a room, said housing having a pair of opposing side walls, a roll-holding mandrel, said side walls having a pair of slots on their inner sides for receiving said mandrel and holding it in operating position, and a rod passing through said side walls and said mandrel for locking said mandrel in operating position.

4. In a toilet roll holder, a housing adapted to be attached to the wall of a room, said housing having a pair of opposing side walls, a roll-holding mandrel, said side walls having a pair of slots on their inner sides for receiving said mandrel and holding it in operating position, a rod passing through said side walls and said mandrel

for locking said mandrel in operating position, and means on said rod outside of said side walls for locking said rod in position.

5. In a toilet roll holder, a housing adapted to be attached to the wall of a room, said housing having a pair of outwardly extending side walls, a hollow roll-holding mandrel, said side walls having a pair of apertures adapted to align with the central hole of said mandrel when the latter is in operating position, said side walls having a pair of slots being in alinement with said apertures, and a rod adapted to be inserted through said apertures into said mandrel for locking the mandrel in position.

In testimony whereof, I have affixed my signature to this specification.

CHARLES E. BEARDSLEY.
